Geo. W. Kirk
ATTORNEY

UNITED STATES PATENT OFFICE.

JOHN JOSEPH DUKET, OF TOLEDO, OHIO.

CLOTHESLINE LOCK.

Application filed September 27, 1920. Serial No. 413,156.

To all whom it may concern:

Be it known that I, JOHN JOSEPH DUKET, a citizen of the United States, residing at Toledo, in the county of Lucas and State of Ohio, have invented certain new and useful Improvements in Clothesline Locks; and I do declare the following to be a full, clear, and exact description of the invention, such as will enable others skilled in the art to 10 which it appertains to make and use the same, reference being had to the accompanying drawings, and to the figures of reference marked thereon, which form a part of this specification.

15 The difficulties encountered by women in putting up clothes-lines and in safely securing them from the mishap of becoming unfastened when loaded with wet fabrics, are familiar domestic troubles. In this operation, as usually performed, the discomforts met and the time consumed by the busy housewife, particularly in cold weather, are some of the disagreeable features of the work. My invention is designed to largely 20 obviate these difficulties and to furnish a cheap, simple and effective device whereby a clothes-line may be quickly, easily and infallibly secured in stretched operative position, without the tying of any sort of knot. 25 and in such fashion that the heavier the load placed upon the line, the more tightly will it be held against displacement.

To these ends, my invention consists of the construction and arrangement of parts 30 hereinafter described, and illustrated in the accompanying drawings, in which—

Figure 1 is a front elevation of my device; Fig. 2, a rear-elevation of the same; Fig. 3, a central vertical sectional-elevation of the 35 same, taken on line $x-x$ Fig. 1; and Fig. 4, a perspective view of the same secured to a post and in operative engagement with a rope or clothes-line.

Throughout the drawings, like reference- 40 numerals represent like parts.

In the drawings, 1 is a bifurcated metal plate, somewhat heart-shaped in outline, and having at its lower point an outwardly projecting lug 2. The central cleft 3, between 45 the right and left wings of the plate, extends to about its middle. At opposite sides of the bottom of the cleft are opposed transverse depressions, 4—4, formed on the inner side of the plate, resulting in two corresponding 50 bulges 5—5 appearing on its outer side.

55 6 is a bar or lever, somewhat longer than

the vertical dimension of the plate 1 and adapted at its upper part to fit loosely in the cleft or slot 3. The bar has, near its middle and integral therewith, two oppositely projecting transverse lugs or trunnions 7, which fit loosely in the depressions 4, and which, when the plate 1 is secured against a flat surface, form a fulcrum upon which the upper and lower ends of the bar tilt in opposite directions. At its top the bar curves outwardly and backwardly, forming a slight segment of a loop or a hook-like portion, as at 8. Near its bottom the bar has a hole or depression 9, into which the lug 2 may enter. 70 This lug 2 and depression 9 therefore provide coacting seats retaining the lever 6 against twisting as to the plate 1. The plate 1 has through each wing, just above the fulcrum referred to, a screw-hole 10, there being but two screws, 10^a, necessary to complete the device.

75 The operation of my device is as follows: The plate 1, having its lugs 7 resting in the depressions 4—4, is secured to the flat surface of a post or wall by means of two screws. The end of the line, or such part of the line as is to be secured, is slipped upward under the lower end of the bar 6, and above the lug 2, which prevents the end of the line 80 from dropping while the line is next looped with a single turn, as at 11, over the hook-like upper part of the bar or lever 6. Now, a pull upon the upper stretch of the line 85 swings the upper part of the bar outwardly, causing the lower part of the bar to swing inwardly, thus causing the line to be tightly clamped between the lower part of the bar and the plate. Of course the stronger the pull upon the line the tighter will be this grip. 90 It will be seen that the screws 10^a are in alignment with the direction of the pull upon the line, and that such pull tends to swing the lower part of the plate inwardly toward 95 the support. The upwardly extended elongated points 12 of the plate, above the screws, tend to prevent the movement of the lower end of the plate away from its support should undue pull be exerted upon the lower end of the lever. By this arrangement, only two 100 screws are necessary in my construction. Proper manipulation of the lower end of the lever will permit the line to be tightened, loosened or removed as may be desired. In the normal position of the line with the lock, 105 direct pulling serves to tighten the grip of the holding means or lever lock, and this is 110

true whether the loop or seat 8 be transverse or terminal.

Having described my invention, what I claim and desire to secure by Letters Patent of the United States, is—

1. In a device of the described character, a bifurcated plate having in its inner face alined opposed recesses, having also in each of its separated portions a screw-hole, and, 10 medially of its lower end, having a seat; and a lever disposed—in part—between the separated portions of the plate and having transverse lugs engaged in said recesses and which form a fulcrum for the lever, said 15 lever being adapted at one end to engage and hold a line and at its other end having inter-engaging coaction with said seat for holding a line for clamping by the lever toward the plate between said fulcrum and 20 said seat.

2. A clothes line lock embodying a mounting plate having a pair of parallel lobes providing therebetween a notch, said lobes adjacent the inner end of the notch having 25 opposing bearing seats, and toward the free ends of said lobes from said seats, each lobe having an opening therethrough as the sole location for plate mounting means, the lobes projecting beyond said pair of openings to 30 position the openings approximately midway between the bearing seats and the lobe free ends, said plate in its extent away from the

lobes having a line receiving seat adjacent the bearing seats, and therebeyond a projection, and a lever having trunnions for engaging the bearing seats of the plate, said lever as extending between the lobes providing a line engaging hook and as extending oppositely over the line seat on the plate serving to hold a line from either direction 40 against said seat, said lever in its terminus remote from the hook having seat coaction with the plate projection.

3. A device of the described character, comprising a lever having a hook-shaped 45 upper end, having, also, near its center two laterally projecting lugs, and having a seat in its lower end, combined with a plate having a vertical slot in its upper part adapted for the reception of the lever, having also two screw-holes at opposite sides of the slot, having also in its inner face at opposite sides of the slot, opposed lateral depressions for the reception of said lugs, and a projection formed on the lower end of the 50 plate arranged to enter the seat for holding a line in clamping position adjacent the lever mounting.

In testimony whereof I affix my signature in presence of two witnesses.

JOHN JOSEPH DUKET.
